J. I. RICHEY,
MANIFOLD HEATER,
APPLICATION FILED DEC. 5, 1917.

1,362,353.

Patented Dec. 14, 1920.

Inventor:
James I. Richey,
by John Elias Jones,
his attorney.

UNITED STATES PATENT OFFICE.

JAMES I. RICHEY, OF CINCINNATI, OHIO.

MANIFOLD-HEATER.

1,362,353.

Specification of Letters Patent. Patented Dec. 14, 1920.

Application filed December 5, 1917. Serial No. 205,696.

To all whom it may concern:

Be it known that I, JAMES I. RICHEY, a citizen of the United States of America, and a resident of Cincinnati, in the county of 5 Hamilton and State of Ohio, have invented a certain new and useful Improvement in Manifold-Heaters, of which the following is a specification.

This invention relates to a handy auxiliary 10 or accessory device that is applicable to the convenient speedy warming or heating of the manifold or inlet-pipe of an internal-combustion engine for automobiles or the like prior to the passage or entrance of the 15 gases into the cylinders thereof, especially in cold weather and just before the starting of the machine, and its object is to provide an independent, open-top cup or receptacle for containing a warm or hot medium such 20 as water, sand, or the like that is poured into said open-top cup, and which cup is adapted to be readily slipped on the upturned elbow of the ordinary manifold and to contain the latter immersed within the heated medium 25 so that the gases passing through said manifold shall be pre-heated before entering the engine cylinders or the combustion-chambers and thereby facilitating the immediate or prompt starting-operation of the engine, the 30 gases being thus more readily and speedily ignited and exploded and, also, more easily maintained so during the further operation of the machine. The machine can thus be started more expeditiously and efficiently, 35 especially, but not essentially, during cool or very cold weather.

The details of structure will be fully hereinafter described and then more particularly pointed out in the claim that follows.

40 In the accompanying sheet of drawings,— Figure 1 is a perspective view of the warming detachable, open-top cup or receptacle that is adapted to contain the manifold or intake and its pre-heating medium, and embodying the preferred form of my invention herein; Fig. 2, a fragmentary perspective of parts of an internal-combustion engine adjacent to and associated with the manifold or inlet-pipe, showing my auxiliary cup or 45 receptacle for containing said manifold and a pre-heating medium therefor; Fig. 3, a central longitudinal section of Fig. 1, but containing the manifold that is shown immersed in the pre-heating medium; and Fig. 4, a 50 detail perspective of the split band or clamp-ring shown immediately below Fig. 1

and used for tightly coupling the lower contracted neck of the said cup in place on the upturned inlet-elbow of the manifold.

1 indicates the gas-explosive part of the 60 shell of the engine, having the usual exhaust-pipe 2 and spark-plugs 3.

4 indicates the usual manifold or inlet-pipe having a lower gas inlet-elbow 5 and controlling devices 6.

7 indicates each of the customary retention-stirrups used for supporting the manifold in place.

8 indicates an elongated tapering cup or receptacle, made of sheet-metal or any other suitable material, and provided with a narrow neck or contracted flange or extension 70 at its lower portion. This cup is preferably split or left open vertically at one end thereof, as shown at 10, and a thin strip of 75 leather, rubber, or other similar material 11 is used to line or pack the lap-joint that is formed by the opposite ends of the cup material in its vertically-split portion. The said strip 11 may be used or not as desired 80 in the joint, and screw-bolts 12 are provided to draw the joint firm and tight against leakage. It is not altogether essential, however, that the cup be made watertight, except, to hold the heating-medium 85 therein long enough to warm or heat the manifold to the desired degree, that would not require more than a minute or two and dependent on the coldness of the weather otherwise.

90 Instead of making the joint as shown so that it may be readily thrown open and the device readily slipped endwise and attached into place or removed from such place, said joint may be soldered or made entirely 95 closed and thus not permitting the cup to be readily placed on the manifold or removed therefrom, which latter feature is not really essential, although somewhat desirable, in the extended use of the machine 100 on which the device is mounted.

A lid or cap (not shown) may be used on the cup for retaining the heat therein, or preventing the entrance of foreign matter.

105 A detachable clamping-ring 13 is provided on the contracted lower end or neck 9 of the cup for securely attaching it in place on the upturned inlet-elbow 5 of the manifold.

Vertical inverted U-shape loops 14 are also 110 provided to further support the cup in suspended place from the exhaust-pipe 2, the

lower twisted and hook ends 15 and 15^a, respectively, of the loops engaging holes 16 in the upper edges of the longitudinal sides of the cup, and easily detachable when necessary.

17 indicates a drain or draw-off cock mounted in the lower portion of the cup for readily emptying the latter when desired.

Hot water, sand, or other medium is provided in the cup when it is desired to warm the manifold and pre-heat the gases passing therethrough before starting, or at the time of starting the machine, and thereby speed or expedite the prompt and positive starting-action of the engine, its gases being pre-heated before entering the combustion-chambers wherein their explosion is also very materially fostered thereby.

The device is intended for use primarily in cold weather, but it can obviously be used at any time or during any season of the year, especially for cold climates to render

the machine more readily and quickly efficient for speedy starting or advancing movement or service.

25

I claim:—

An accessory, detachable warming-attachment for manifolds of internal-combustion engines, comprising an independent, auxiliary, open-top cup adapted to contain both the manifold and the preliminary hot-water or other hot loosely-applied heating-medium and having a lap or split joint to facilitate its removable attachment in place for said accessory use, a clamping-ring adapted to detachably-fasten the lower contracted end or neck of the said open-top cup on the upturned elbow of the manifold, a pair of suspension-loops to detachably hold the auxiliary, open-top cup in using position, and a drain-cock in the bottom of said cup, substantially as shown and described.

JAMES I. RICHEY.
